GUN SIGHT AND MOUNTING

George D. Russell, Ysleta, Tex.

Application October 31, 1940, Serial No. 363,749

6 Claims. (Cl. 33—47)

This invention relates to an improved construction of gun sight and mounting, and aims particularly to provide an improved construction of front and rear gun sights so constructed that the vision of the marksman will not be obstructed while sighting to thereby provide for greater accuracy.

Other objects of the invention are to provide a gun sight having means to provide allowances for elevation, windage and lead on swiftly moving objects; means for quickly substituting different sighting units to compensate for varying light conditions and for peculiarity of eyesight; and means whereby the adjustment of the sights and the interchanging of the sighting units may be made with the use of a few tools.

Still another aim of the invention is to provide a gun sight wherein the front and rear sights, when alined, will resemble a spider web with a small opening or snake eye in the center thereof in which the target is adapted to be centered.

Other objects and advantages of the invention will hereinafter become more fully apparent from the following description of the drawing, which illustrates a preferred embodiment thereof, and wherein:

Figure 1 is a side elevational view of a portion of a rifle barrel, shown equipped with the sight,

Figure 2 is a side elevational view of one form of the front sight,

Figure 3 is an edge view partly in section and partly in elevation of the same,

Figure 4 is a view similar to Figure 2 of the rear sight of the form shown in Figures 2 and 3,

Figure 5 is an edge view partly in section and partly in elevation of the same,

Figure 6 is a side elevational view showing the front and rear sights of Figures 2 to 5, as they would appear to the marksman when correctly aligned,

Figure 7 is a similar view of another form of the invention,

Figure 8 is a view similar to Figure 4 of the rear sight of the modified form, and

Figure 9 is a view similar to Figure 2 of the front sight of the modified form.

Referring more particularly to the drawing, wherein like reference characters designate like or corresponding parts throughout the different views, 10 designates a portion of a rifle barrel having transversely disposed dovetail shaped grooves in the upper side thereof, one adjacent each end of the barrel, said grooves being designated 11. A front sight, designated generally 12 is mounted adjacent the forward end of the bar-

rel, and a rear sight, designated generally 13, is mounted adjacent the rear end thereof. The front sight 12, as best seen in Figures 2 and 3, includes a cylindrical shell member 14, the bore of which is enlarged at one end as seen at 15. A portion of the shell 14 is attached to a dovetail shaped base member 16 which is sized to fit the groove 11, at the forward end of the barrel 10, for mounting the shell 14 of the front sight 12 on the forward end of the barrel.

The rear sight 13 includes a shell 17 which is likewise cylindrical in shape and recessed at one end at 18 similarly to the recessed portion 15 of the shell 14. Shell 17 is provided with a depending tenon 19. A dovetail shaped base member 20 is sized to fit the groove 11 at the rear end of the barrel 10, and is provided with an elongated upwardly opening groove 21 to receive the tenon 19, and which is substantially longer than said tenon so that the shell 17 may be adjusted laterally relatively to the axis of the barrel 10 to provide for windage adjustments. The base member 20 is provided with a set screw 22 which opens into its groove 21 and which is adapted to engage one side of the tenon 19, which side is preferably roughened, as seen in Figure 5, for retaining the shell 17 in any one of a plurality of adjusted positions. The tenon may likewise be raised relatively to the groove 21 and clamped in any one of a plurality of raised positions by the set screws 22 for elevating the shell 17 relatively to the base 20 to provide for adjusting the elevation of the sight.

The enlarged portions 15 and 18 form seats for split spring rings 23, the ends of which rings, at the split portions thereof are turned inwardly to form finger holds 24 by means of which the rings 23 may be contracted for applying them to or removing them from the portions 15 and 18. Each of the rings 23 is provided with a blade 25, the ends of which form arms 26 which converge toward the center of the ring 23. The remote ends of the arms 26 are suitably secured to the inner side of the ring 23. The intermediate portion 27 of the blade 25 is bowed inwardly to form a substantially semi-circular sighting element which is concentrically disposed in the ring 23 and around a half of the axis thereof. The blade 25 is disposed in diametrically opposed relationship to the split portion of the ring. The half of the ring 23 which is contiguous with the blade 25 is coated with an illuminous substance, as seen at 28, and the remote ends of the supporting arms 26 are similarly coated.

The shell 14 is provided at its bottom with an

inwardly projecting tapered lug 29 which extends from the recessed portion 15 thereof and which is adapted to be disposed between the finger holds 24 of the ring 23 which is mounted therein to prevent said ring 23 from being turned relatively to the shell 14, and to position the blade 25 in the upper portion of the opening formed by the ring and so that the sight element 27 will be in an inverted position, as seen in Figure 2. The portion 18 of the shell 17 is provided with a similar projection 29 at the top thereof for similarly preventing the rotation of the ring 23 which is mounted therein and positioning the blade 25 in the lower portion of the shell 17, so that its sighting element 27 will open upwardly.

When the sights 12 and 13 are thus assembled and mounted on the barrel 10, and when the sights are correctly aligned by the marksman they will appear to the marksman, as seen in Figure 6, with the sight elements 27 forming a circle or snake eye and the arms 26 combining therewith to form a simulated spider web. With the sights thus brought into alignment, as seen in Figure 6, the target is centered in the opening formed by the sight elements 27. It will thus be seen that the sights 12 and 13 will not obscure the marksman's vision of the target.

For night shooting, the luminous portions 28 of the rings 23 will form a circle visible to the marksman when the sights are aligned, and the luminous portions 28 of the arms 26 will be pointing toward the center of the shells 14 and 17 so that the marksman can align the target centrally of the luminous portions 28 of the arms 26.

If desired, the base 20 may be provided with markings or calibrations as seen at 30 for correctly adjusting the sight 13 to compensate for right or left windage.

In Figures 7, 8 and 9 another embodiment of the invention is disclosed wherein the shell 14' of the front sight 12' is substantially arch shaped and provided with a substantially flat base. The blade 26' is mounted in the upper portion of a ring 23', which ring is shaped to fit the opening of the arch 14'. The ring 23' is split at its bottom to form the finger holds 24'. The blade 26' is arranged in the upper portion of the ring 23' and its sight element 27' is disposed in an inverted position. The sight 12' is provided with a base 16' by means of which it may be mounted in the groove 11 at the forward end of the barrel 10. The ring 23' may be applied or removed by contracting the finger holds 24' in the same manner as the ring 23.

The rear sight 13', as seen in Figure 8, likewise includes an arch shaped shell 17', the height of which is substantially less than that of the shell 14'. A ring 23'' is shaped and sized to fit into the shell 17' and is split at its bottom and provided with the finger holds 24'' for contracting the ring 23''. Ring 23'' is provided with a blade 26' which is mounted in the lower portion thereof with its sight element 27' opening upwardly. The sight 13' is provided with a tenon 19' for engaging a groove 21' in a base 20 and which is adjustable relatively thereto in the same manner that the tenon 19 is adjustable in the recess 21 for allowing for windage and elevation. The base 20' is shown provided with two set screws 22' for retaining the shell 17' in any one of a plurality of adjusted positions. It will be obvious that either embodiment of the invention may be provided with one or two set screws depending upon the size of the rear sight for holding the rear sight in adjusted positions. The

upper portion of the ring 23' and the remote ends of the arms 26' of its blade 25' are coated with a luminous substance, as seen at 28, and the lower portion of the ring 23'' and the remote ends of the arms 26' of its blade 25', as illustrated in Figure 8, are coated with the luminous substance 28.

When the sights are correctly aligned, as illustrated in Figure 7, they will appear to the marksman, as seen in Figure 7, with the sight elements 27' combining to form a circle. The luminous portions 28 of the members 23' and 23'' will combine to form an arch shaped luminous portion with the remote ends of the arms 26' pointing toward the center of the arch. It will be obvious that the front and rear sights 12' and 13' will function in the same manner as the front and rear sights 12 and 13, and as previously described.

The members 23, 23' and 23'' are made readily removable so that the shells 14 and 17 and 14' and 17' may be provided with blades 25 and 25' of different thicknesses and colors to suit the vision of the marksman and to compensate for varying light conditions, and these supporting members may be quickly and easily removed and replaced.

While the gun sights are shown applied to a rifle barrel they are obviously well adapted for use with other types of firearms such as pistols and revolvers.

Various modifications and changes in the construction and arrangement of the parts forming the two embodiments of the invention, as disclosed, are contemplated and may obviously be resorted to.

I claim as my invention:

1. A gun sight comprising shell members mounted adjacent the ends of a gun barrel, ring members detachably mounted in said shell members, each of the ring members being provided with a pair of converging supporting arms, and a semi-circular sighting element connected at its ends to the adjacent ends of a pair of said supporting arms and disposed concentrically within the ring, the sighting element of one of the rings being disposed above the axis thereof and the sighting element of the other ring being disposed beneath the axis of the last mentioned ring so that the sight elements will combine to appear to the shooter as a circle when the sights are aligned with a target.

2. A gun sight as in claim 1, said ring members having opposite portions, which are contiguous with the supporting arms thereof, provided with a coating of a luminous substance, the remote ends of said pairs of supporting arms being coated with the luminous substance, and said luminous portions of the ring members combining to appear to the shooter as a circle when the sights are aligned and the luminous portions of the arms forming luminous projections pointing toward the center of the luminous circle and in which the target is adapted to appear to be centered when the sights are aligned thereon.

3. A gun sight as in claim 1, and means for preventing the ring members from turning within the shell members.

4. A gun sight as in claim 1, said ring members each comprising a split ring, said supporting arms being remotely disposed relatively to the split portions of the rings, the ends of each of the rings being turned inwardly to provide finger holds for compressing the ring for applying or removing it, and said shell members having in-

47

2,256,411

3

wardly extending projections adapted to be disposed between pairs of the finger holds of the rings for mounting the rings in certain positions in the shells.

5. A gun sight as in claim 1, the shell member adjacent the rear of the gun barrel being provided with a depending tenon, a base member having a groove for receiving said tenon, said groove being sized to permit adjustment of the tenon horizontally and vertically relatively to the 10 base member, and set screw means for securing the tenon in a fixed position in the groove.

6. A gun sight comprising shell members

mounted adjacent the ends of a gun barrel, said shell members having arcuately shaped upper portions and substantially flat lower portions, yieldable supporting members detachably mounted in said shell members, semi-circular sight elements carried by said supporting members and disposed therewithin, one of said sight elements being disposed in an upright position and the other of said sight elements being inverted, and said sight elements being arranged relatively to said shell members to appear to form a circle when the sights are alined.

GEORGE D. RUSSELL.
